UNITED STATES PATENT OFFICE.

JOHN DELL LEMEX, OF TULSA, OKLAHOMA.

ADJUSTER BAR.

Application filed May 5, 1921. Serial No. 466,880.

To all whom it may concern:

Be it known that I, JOHN D. LEMEX, a citizen of the United States, residing at Tulsa, in the county of Tulsa and State of Oklahoma, have invented certain new and useful Improvements in Adjuster Bars, of which the following is a specification.

This invention relates to an adjuster used in connection with oil pumping outfits for transmitting motion from a walking beam to a pump operating rod.

In operating oil and similar pumps, the usual practice is to drive the pump from a walking beam which is rocked by any suitable source of power. The adjuster must be so mounted on the walking beam as to transmit only a reciprocable movement to the pump, while the end of the walking beam oscillates through an arc. The adjuster must also have a clamp for adjustably engaging the pump operating, or, as it is termed, the "polished rod" so that the piston of the pump will be in proper position and not too low or too high when the walking beam is at either limit of its movement, otherwise, injury to the pump would result. In the usual form of adjuster, it is necessary to slot the end of the walking beam. Such adjusters are usually T-shaped with a cross bar engaging on the top of the walking beam and the stem depending through the slot.

Furthermore, with the usual form of adjuster as now attached to walking beams, it is necessary, when it is desired to elevate or place pumping rods in the well, for a workman to climb on top of the walking beam and loosen the member known as the "clamping board" which holds the adjuster in place, whereby the adjuster may be moved out of the way of the rods to be inserted or elevated. This work entails a loss of considerable time, and is inconvenient and sometimes dangerous.

An object of the present invention is to provide an adjuster which may be quickly and accurately positioned on the walking beam and will not require slotting thereof, and which may be cheaply constructed and conveniently manipulated.

With my device, the adjuster, by means of its novel connection with the walking beam, need not be loosened or removed when a rod is being elevated or inserted, the construction enabling it to be swung back or to be swung over the end of the walking beam out of the way.

In the accompanying drawings, which illustrate an embodiment of my invention, Fig. 1 is a front view of the adjuster showing the clamps attached to metal straps;

Fig. 2 is a similar view showing wire cables substituted for the straps;

Fig. 3 is a side view of a portion of the adjuster, showing how it is carried by the walking beam;

Fig. 4 is a section on line IV—IV of Fig. 1;

Fig. 5 is a section on line V—V of Fig. 2;

Fig. 6 is a detail section on line VI—VI of Fig. 5 with the collar omitted;

Fig. 7 is a section on line VII—VII of Fig. 2;

Fig. 8 is a side elevation of a modified construction; and

Fig. 9 is a section on line IX—IX of Fig. 2, but showing the modified construction with cables in place of straps.

Referring to Fig. 3, of the drawings, A is a walking beam having a transverse groove across its end, and B an adjuster board of the kind usually employed in connection with adjusters.

The adjuster comprises a stirrup having a rounded cross member 5 which connects the upper ends of depending side members 6. I prefer that the stirrup be formed as an integral structure, as shown, but it need not necessarily be so made. Between the lower ends of the side members 6 is a spacing block 7 which has channeled sides 8 (see Fig. 7). One face of the block is preferably recessed and on this face is a longitudinally extending projection 9 having a rounded upper end 9' and having recesses 10 formed in its sides. At 11 are elongated openings in the block 7 which open into the channels 8.

In the construction shown in Fig. 1, straps 12 are received in the channels 8, and bolts 13, passing through side arms 6, 100 straps 12 and block 7 hold the several parts together. The straps 12 extend downwardly a suitable distance and carried at their lower ends is a suitable clamping means of any preferred construction. I 105 have shown jaws 14 welded or otherwise secured to the ends of the straps. Through the jaws 14 are openings 14^a for a purpose to be hereinafter described.

Embracing the lower ends of the straps 110 is a collar 15 which may be moved up and down thereon or removed entirely, as indi-

cated in dotted lines in Fig. 1. The pump operating or polished rod is indicated at C. In the collar 15 is a set screw 16 for forcing the jaws together. When the polished rod 5 has been properly adjusted, set screw 16 may be turned to bring the jaws 14 into clamping relation with the rod.

In operation, the stirrup is first placed on the walking beam A and clamped into place 10 by adjuster board B. Then the polished rod and the adjuster are manipulated until in proper position and then clamped. Upon 15 oscillation of the walking beam, the adjuster is reciprocated and this motion is transmitted to the polished rod. By reason of the cross member 5 of the stirrup being rounded, the connection with the walking beam is in effect a pivoted one, so that the 20 adjuster does not swing in an arc with the end of the beam.

In place of straps 12, a wire cable 20 may be used. The cable is looped and placed over projection 9. U-bolts 21 are then passed around the cable and through openings 11. The recesses 10 serve to give sufficient space for manipulating the U-bolts. The ends of the U-bolts extend into channels 8, where the usual nuts are applied, as shown in Fig. 7. Then the block is connected with the depending side members of the stirrup by the bolts 13. The depending ends of the cable are suitably connected with clamping means of any preferred construction.

35 As shown, the clamping means comprise a pair of jaw members 14 similar to those shown in Fig. 1. One of the jaw members is attached to one of the cable ends and one of the jaw members to the other cable end, 40 the attachment being effected by passing the cable ends through openings 14^a in their respective jaws and babbittting them, as shown in the detail sectional view (Fig. 6). Thus, the jaws are constructed the same for use 45 with cables or with straps.

This construction is used in the same way as is the construction in Fig. 1, but its application is limited to wells in which the oil is sufficiently thin to permit the plunger 50 to lower by gravity at the same rate the walking beam rocks downwardly. It will, of course, be obvious that instead of having an interchangeable spacing member adapted to be used with either rigid or flexible clamp 55 carrying means, separate blocks might be employed.

It may be desirable to place the stirrup at an angle to the block, and in the construction shown in Figs. 8 and 9, this may be 60 done. The sides of the stirrup are indicated at 25, and at 26 is a slot therein. The block is indicated at 27. The upper bolt 28 passes through the block and through 65 the slots in the members 25. The lower bolt passes through the parts in the usual man-

ner. The stirrup may be adjusted to the proper angle and then the nuts on the bolts tightened, and the parts thus secured in the desired position.

With this form of adjuster, it will be seen that when it is desirable to insert a pump operating rod, or to elevate one, the adjuster can be swung back or swung over 70 the end of the walking beam out of the way, the movement not being limited by 75 contact with the walls of a slot, as is the usual T-form of adjuster, as heretofore used.

Various changes and modifications may be made in the construction shown without departing from the broad features of my 80 invention.

What I claim is:

1. An adjuster for transmitting motion from a walking beam to a pump operating rod comprising an integral stirrup having side members and a cross member connecting the upper ends of the side members, means for holding the lower ends of the side members in fixed spaced relation, and spaced apart flexible extensions of greater length than the side members of the stirrup depending from the spacing means, and having clamping means at the lower ends thereof, said clamping means being co-axially aligned with the spacing means, said spacing means providing the upper limit to which a pump rod engaged in the clamp may reach, whereby the pump rod with which the adjuster is used will always be well below the stirrup to provide clearance for a walking beam.

2. An adjuster for transmitting motion from a walking beam to a pump operating rod comprising a stirrup having a cross member for engaging a beam and depending side members, an adjustable spacing member connecting the depending side members of the stirrup, and clamp carrying means depending from the spacing member.

3. An adjuster for transmitting motion from a walking beam to a pump operating rod comprising a stirrup having a cross member for engaging the beam and depending side members, a spacing member connecting the depending side members, spaced apart straps separate from the stirrup secured to and depending from the spacing member, and clamping members on the lower ends of the straps for engagement with a pump operating rod.

4. An adjuster for transmitting motion from a walking beam to a pump operating rod comprising a stirrup having a cross member for engaging the beam, and depending side members, a spacing member connecting the depending side members, clamp carrying means depending from the spacing member and having a clamp at the lower end thereof, and means whereby the 125 130

angle of the stirrup may be adjusted with relation to the spacing member.

5. In an adjuster, a stirrup for engagement with a walking beam, a spacing member connected with the stirrup, and means whereby the angle of the spacing member may be varied with relation to the stirrup.

6. An adjuster for transmitting motion from a walking beam to a pump operating member comprising a stirrup having a cross member and depending side members, a spacing member between the lower ends of the side members, and means on the spacing member arranged to accommodate either

15 flexible or rigid clamp carrying means.

7. An adjuster for transmitting motion from a walking beam to a pump operating rod comprising a stirrup having depending side members, an adjustable spacing block

interposed between said side members, 20 spaced apart clamp carrying means suspended from the adjustable spacing block to a considerable distance below said spacing block, and a clamping means carried at the lower ends of said clamp carrying means 25 and arranged to embrace a pump operating rod in such manner that the pump operating rod may extend up between the spaced apart clamp carrying members in alignment with the longitudinal axis of said 30 clamp carrying means.

In testimony whereof I affix my signature in presence of two witnesses.

JOHN DELL LEMEX.
